TREATING HYDROCARBON OIL

Filed Nov. 11, 1927

UNITED STATES PATENT OFFICE

CLAUDE W. WATSON, OF PORT ARTHUR, TEXAS, ASSIGNOR TO THE TEXAS COMPANY, OF NEW YORK, N. Y., A CORPORATION OF DELAWARE

TREATING HYDROCARBON OIL

Application filed November 11, 1927. Serial No. 232,661.

This invention relates to a process of treating hydrocarbon oil and more particularly to a process for the separation of the various components of petroleum by fractional distillation. The invention comprises a continuous process in which petroleum oil may be subjected to distillation by passing through a battery consisting of a series of stills fitted with suitable fractionating towers, the individual stills of the series being maintained at progressively higher temperatures. Various fractions of the oil charged to the battery are collected from corresponding groups of stills of the series. In each group of stills the oil is conveyed from each individual still directly to the next succeeding still with the exception of the final still of each group, in which case the oil is conveyed from the preceding still to the fractionating tower of the final still.

In the distillation of petroleum, wherein the various fractions such as gasoline, kerosene, gas oil, lubricating oil, and the like are separated, it is desirable to effect the separation as thoroughly and in as efficient a manner as possible. Thus, to correspond with the usually accepted specifications and properties it is undesirable that a gasoline fraction obtained from petroleum should contain any of the kerosene fraction as the presence of such material will tend to raise the end point and change the desired distillation range of the gasoline. From the same standpoint it is undesirable that a kerosene fraction shall contain any part of the gasoline fraction as this would result in the lowering of the initial boiling point of the kerosene and would also change its desired distillation range.

In the ordinary methods of distilling petroleum in which a continuous battery of stills is employed the boiling range of the distillates obtained from the stills is not such as to permit of thorough separation between the various fractions, and as a result, it is found that products from such ordinary processes usually have to be redistilled to eliminate appreciable quantities of other products of different boiling range. For example the fraction containing the gasoline constituents

must be redistilled to lower the end point, while the kerosene fraction will usually have to be subjected to steam distillation to increase its initial boiling point. By the application of well designed fractionating towers to a continuous battery of stills, the separation effected will be made more complete but even with such improved apparatus it is found very difficult to obtain the desired complete separation of the various fractions collected.

The present invention provides a method of distilling petroleum oil in a continuous battery of stills whereby a substantially complete separation of the various fractions collected may be brought about. The invention may be more clearly understood when considered in connection with a suitable apparatus such as that shown in the accompanying drawing which illustrates in diagrammatic form an apparatus and flow chart in which the invention is embodied. It will be understood that the invention is in no way limited by the diagrammatic representation of apparatus, this being provided solely for illustrative purposes.

Referring to the drawing, the diagram illustrates a battery of six shell type stills so arranged for distilling crude petroleum that distillates will be obtained from the first three stills which, after condensing, will be found suitable for blending to produce a gasoline fraction. From the fourth and fifth stills are obtained distillates suitable for blending to form a kerosene fraction, while from the last still a distillate corresponding to gas oil may be collected. In the drawing the six stills are represented by the numerals 10^a, 10^b, etc., the first five of these stills being fitted with suitable fractionating towers, preferably of the type usually known as bubble towers, 11^a, 11^b, etc. The last still of the series, 10^f, from which a gas oil fraction is to be collected, is fitted with a vapor heat exchanger 12 instead of the fractionating towers of the type used on the other stills in the battery. A source of supply 13 of the oil which is to be charged to the battery of stills is provided, the oil being conveyed to the stills through the connections 14 by

charging pump 15. The charge oil may enter the battery through the first still 10^a or through the tower 11^a, or may be distributed between the still and the tower, and the point of entry may be controlled by means of the valves 26 and 17. Suitable piping connections 18^a, 18^b, etc. are provided for the removal of the vapors from the tops of the fractionating towers 11^a, 11^b, etc. and from the vapor 5 heat exchanger 12 and extend to suitable condensers (not shown). The several vapor lines 18^a, 18^b, etc. are connected as indicated in the drawing for the purpose of combining vapors from the corresponding stills to produce the desired distillate. Connections 19^a, 19^b, etc. are provided for the introduction of reflux cooling to the fractionating towers and the valves 20^a, 20^b, etc. are provided for the regulation of the quantity of reflux liquid 10 supplied. Overflow lines 21^a, 21^b, and 21^c are provided for intercommunication of stills 10^a—10^b, 10^c—10^d, and 10^e—10^f, while stills 10^b—10^c, 10^d—10^e are connected through the lines 22^b, 23^b, 22^d, and 23^d, respectively, and 15 the pumps 24 and 25. From the final still in the battery 10^f, the connection 21^f is provided for the withdrawal of the undistilled residuum.

In operating the process comprising the 20 invention in connection with the apparatus illustrated, the procedure may be as follows:

A suitable charging stock is provided 25 which may consist of any petroleum oil which it is desired to separate into several fractions by means of distillation. Thus the charging stock may consist of a distillate oil, a residual oil, or a crude petroleum but in the present description and for the purpose of illustrating the invention the operation 30 when charging a crude petroleum of the type obtained from the North Central Texas fields will be discussed.

The crude charging stock from the source 35 of supply 13 is forced by the pump 15 through the line 14 to the battery, passing first through the vapor heat exchanger 12 wherein an exchange of heat is effected between the hot vapors from the still 10^f and the cool charge. In the particular example under 40 consideration the charge may be heated to approximately 200° F. while passing through the vapor heat exchanger. From the vapor heat exchanger 12 the heated charge passes 45 through the residuum exchanger 16 wherein its temperature is further elevated by the heat absorbed from the hot residuum which is withdrawn from the final still of the series, 10^f. From the exchanger 16, the heated charge is carried by the line 14 to the first 50 of the battery of stills. The charge may be introduced directly into the still 10^a or it may be introduced into the fractionating tower 11^a, preferably at a mid-point, and in 55 the present example it is desirable to intro-

duce the charge into the tower 11^a at a mid-point.

The stills 10^a, 10^b, etc. are maintained at successively higher temperatures by means of suitable furnaces (not shown). The arrangement of stills as shown in the drawing may be in three groups, the first three stills, 10^a, 10^b, and 10^c constituting the first group, from which a gasoline fraction is collected. The next two stills, 10^d and 10^e, constitute the second group of the series and from these stills a kerosene distillate is collected. Still 10^f may be considered as the third group, and from this still a gas oil distillate is obtained. The charge after entering still 10^a undergoes 60 distillation therein and overflows into still 10^b through the overflow line 21^a. After undergoing further distillation in still 10^b the oil is pumped from still 10^b through the lines 22^b and 23^b by means of the pump 24 into a mid-point in the tower 11^b. The pump 24 may be any suitable type of reciprocating or rotary pump and it has been found that a steam lift may be satisfactory for use in elevating the oil at this point. Thus it will be observed 65 that in the group of three gasoline stills the oil overflows from the first still to the second still but is pumped from the next to the last still of the group into a mid-point of the tower of the last still of the group. The contents of the stills may be maintained at any desired temperature but in the particular operation described herein still 10^a may be maintained at a temperature of 410° F., still 10^b at 480° F. and still 10^c at 525° F. The 70 distillate fractions taken from the tops of the corresponding towers are condensed and combined to form the gasoline fraction of the crude charge, which fraction is so distilled as to have an end point of approximately 400° F. Steam may be introduced into any or all of the stills during distillation by means of suitable connections (not shown) as is well 75 known to those familiar with the art of petroleum refining, and the exact temperatures of the stills will vary somewhat in accordance with the amount of steam thus introduced. In order that proper fractionation 80 may be obtained from the fractionating towers 11^a, 11^b, and 11^c, cooling is supplied to the top of the towers by means of the reflux connections at 19^a, 19^b, and 19^c. The material used for reflux may consist of the liquid condensate from corresponding towers or any 85 other suitable material, the quantity supplied the individual towers being regulated by means of the valves 20^a, 20^b, and 20^c.

From the last still, 10^f, of the group of gasoline stills the charge overflows into the first 90 of the group of kerosene stills. In this particular illustration of the process there are only two kerosene stills, 10^d and 10^e, and accordingly the charge is pumped from the first 95 of the group of kerosene stills, 10^d, to a mid-

point in the tower of the second or last still of the group, 10^e. These stills may be maintained at temperatures of approximately 540° F. and 560° F., respectively. Suitable reflux 5 is supplied the fractionating towers of the kerosene stills through the connections 19^a and 19^e, the quantity being regulated by means of the valves 20^a and 20^e. The vapors from the fractionating towers 11^d and 11^e 10 are condensed and combined to form the kerosene fraction obtained from the crude charge, the distillation being so regulated that the kerosene will have an end point of approximately 500° F. From the last still, 10^e, of the 15 group of kerosene stills the oil overflows into the still 10^f in which a portion or all of the gas oil fraction of the charge is distilled overhead through the vapor heat exchanger 12, the vapors giving up their heat to the incom- 20 ing charge, as has been mentioned before. The residuum is withdrawn from the still 10^f through the connection 21^f and the exchanger 16 wherein it gives up a portion of its heat to the charge. The residuum may be suitable 25 for fuel oil or for lubricating oil stock or for other purposes.

The illustration of the invention which has been given in the preceding paragraphs has shown, in a continuous battery of stills, 20 groups of stills producing distillates suitable for gasoline, kerosene, and gas oil fractions. It is to be understood of course that any number of stills may be employed in the series and that the individual groups within the series 25 may contain any desired number of stills, which may vary in accordance with the characteristics of the charging stock. For example, a certain charging stock may contain a large quantity of gasoline and very little 30 kerosene in which case the group of gasoline stills may contain four or even more stills, while the kerosene group may even consist of a single still. However, it is possible that a charging stock may be used which would contain 35 a large proportion of kerosene but practically no gasoline in which case the first group of stills may yield a kerosene distillate.

The advantages obtained from the practice 30 of the invention in connection with the operation of a continuous battery of shell stills consist chiefly in the more thorough separation of the various fractions which it is desired to obtain from the charging stock. For example, in ordinary operation of a battery 35 of stills, even those equipped with efficient fractionating towers, it will be found that if the gasoline fraction is run to a required end point, say for example 400° F., the kerosene fraction will contain some gasoline and will 40 have an initial boiling point well below 400° F., say for example 360° F. This condition is due to the fact that the charge, in over- 45 flowing through the series of stills, reaches the last gasoline still in such a condition that it contains an appreciable quantity of ma-

terial which may be considered as gasoline, that is, boiling below 400° F. Due to the equilibrium conditions obtaining in the still in accordance with the well-known laws of partial vapor pressures it is very difficult to 70 avoid having the charge flowing out of the last gasoline still thoroughly stripped of the lower boiling or gasoline constituents and accordingly this charge, when flowing into the first kerosene still, which is maintained at a 75 somewhat higher temperature, immediately vaporizes the lighter constituents which accordingly pass overhead into the kerosene fraction. However, when the battery is operated in accordance with the present invention the charge from the next to the last of the group of gasoline stills is pumped into the fractionating tower of the last of the group of gasoline stills. Thus the charge, 80 in flowing downward through the fractionating column on the last of the group of stills, meets the upward flowing heated vapors and is stripped of its entire gasoline content before it reaches the still itself. It is found that the oil within the last of the group of 85 gasoline stills contains practically no material within the gasoline range of distillation and accordingly when carrying on the distillation in connection with the present invention, a gasoline may be easily obtained 90 which will have an end point not exceeding, 95 and in some instances several degrees lower than, the initial boiling point of the kerosene.

The foregoing discussion of the operation 100 of the group of gasoline stills applies also to the group of kerosene stills. Thus, in ordinary operation of a continuous battery of stills in which the oil merely overflows from one still to the next, due to the insufficient fractionation and separation, a portion of 105 the kerosene will pass into the gas oil still and will accordingly be distilled overhead with the gas oil fraction. However, when operating a continuous battery of stills in accordance with the present invention it will 110 be found that a kerosene of a given end point, say for example 500° F., may be obtained, together with a gas oil fraction having an initial boiling point in excess of 500° F. thus 115 showing that there is approximately no kerosene passing over into the gas oil fraction.

Further advantages resulting from the 120 operation of a continuous battery of stills in accordance with the invention, in addition to the more thorough separation of the various fractions collected, is experienced in the increase in the charging capacity of the battery, its more flexible operation, and the saving in fuel effected.

Obviously many modifications and variations 125 of the invention, as hereinbefore set forth, may be made without departing from the spirit and scope thereof, and therefore, only such limitations should be imposed as are indicated in the appended claims. 130

I claim:

1. The method of distilling petroleum oils which comprises establishing a series of pools of oil maintained under conditions of distillation, each pool communicating with a fractionating zone, said series of pools of oil being divided into two or more separate groups, continuously charging oil into the first pool of the series, collecting separate distillate fractions from each of the said groups and introducing oil from the next to the last pool of each group to an intermediate point in the fractionating zone of the last pool of the same group.
2. The method of distilling crude petroleum which comprises establishing a series of pools of oil maintained under conditions of distillation, each pool communicating with a fractionating zone, taking off distillates suitable for forming a fraction of substantially the boiling range of gasoline from a group comprising the first several pools of the series, taking off distillates suitable for forming a fraction of substantially the boiling range of kerosene from a group comprising the next succeeding pools of the series and introducing the oil into the last pool of each of said groups at an intermediate point in the corresponding fractionating zones.
- 30 In witness whereof I have hereunto set my hand and seal this 26th day of October, 1927.
